UNITED STATES PATENT OFFICE

CHRISTIAN J. TOERRING, OF PHILADELPHIA, PENNSYLVANIA.

ELECTRIC-ARC LAMP.

No. 820,220.

Specification of Letters Patent. Patented May 4, 1909.

Application filed May 3, 1906. Serial No. 315,056.

To all whom it may concern:

Be it known that I, CHRISTIAN J. TOERRING, a citizen of the United States, residing in the city and county of Philadelphia, State of Pennsylvania, have invented a new and useful Electric-Arc Lamp, of which the following is a specification:

The purpose of my invention is to secure simplicity in the control of the carbon feed in 10 an inverted lamp.

A further object of my invention is to apply gravity feed to a lamp of inverted type.

A further object of my invention is to release or apply a counter-weight feed, avoiding direct clutching of the carbon or carbon holder.

A further object of my invention is to dispense with the use of objectionable springs and other artificial means of supporting an 20 adjustable lower carbon against gravity.

Figure 1 represents an elevation partly in section of a lamp embodying my invention. Fig. 2 represents an enlarged elevation also partly in section, showing a portion of the 25 structure of Fig. 1. Fig. 3 represents a longitudinal section upon line 3—3 in Fig. 2. Fig. 4 represents a section upon the line 4—4 of Fig. 2. Fig. 5 represents a plan of part of the structure shown in Fig. 4. Fig. 6 represents 30 a diagrammatic wiring view.

Similar numerals of reference indicate corresponding parts in the figures.

Referring to the drawings, 1 designates my lamp, which consists of a preferably central tube 2, which in my construction becomes the receiver and guide for a carbon holder 3 and the lower or positive carbon 4. At its lower end the tube carries a block 6, which forms a support for my counter-weight 5. 35 guide 7, and the lower member 8 of the dash pot 9, the lower member being preferably the piston member as shown. The cylinder 10 in itself forms a protection against injury from dirt or other foreign matter. The block 6 forms a support also for my solenoid 11. The solenoid 11 is supported directly from the plate 12, insulated from the block 6 in 40 any suitable manner.

Below the block 6 and insulated therefrom, 45 I preferably place a disk 13 to which is attached a bolt 14, the plate or disk and bolt forming a convenient means of spacing and attaching my casing 15 to the lamp at the lower end, the attachment being by means of 50 nut 16. At the upper end this casing 15 is spaced from the lamp parts by means of a

disk 17, which is insulated from the tube 2 and from the other parts of the interior of the lamp structure hereinbefore enumerated in any suitable manner. The disk 17 carries 60 preferably porcelain resistance cores 18, 19 and coils 20. One of these resistances is capable of adjustment by sleeve 20' in the usual manner.

Upon the top of the disk 17 are mounted 65 clips 21 for attachment of a globe 22, which globe rests upon a plate 23 electrically insulated from the disk 17, and permissibly in electric contact with the tube 2. In the construction which I have shown, the plate 70 23 is insulated from the disk 17 at its point of support upon said plate, namely under the feet 24. Any means of attachment of these parts which will secure the necessary rigidity and insulation may of course be 75 used.

In proximity to the disk 17 and in any suitable manner I secure the lower reflector 25, which may be fastened to the disk or the casing. I preferably fasten it to the casing 80 15 by means of set screws 26 engaging a preferably rolled ring 27 in the said casing. The advantage of this construction is that by loosening the set screws 27, the reflector may be dropped throughout all or any desired portion of the length of the casing, or even removed therefrom over ring 28. The operative parts of the lamp is supported from the plate or disk 17 by means of rods within protecting tubes 29 and 30, which 90 95 may evidently be of any desired number other than two, the rods constituting conductors insulated from the tubes. These conductors convey the current to and from the lamp, the current being applied to one conductor and received from the other at and by means of the binding posts 31 and 32, which are insulated at 33 and 34 from the tubes 29 and 30 and from the support 35 to which the suspending and insulating roller 36 100 105 is attached by means of ears 37. It is thus to be seen that the weight of the lamp resting upon the suspension 37 is transmitted through the support 35, the rods, the disk 17 and the tube 2 to the block 6, which supports those operative parts of the structure which are not supported directly from the plate 17.

The reflector 38 is so arranged as to reflect a minimum of light upon the lower reflector 25, 110 either from the arc itself or of light which has been initially reflected by said reflector 25,

being reentrant near its central portion and forming a concaved annulus as viewed from below. The object of this construction is that practically the entire light reflected by 5 the reflector 38 passes out between its outer edge 39 and the outer edge 40 of the lower reflector causing a most desirable diffusion of the light thus distributed. The reflector 38 is supported from the support 35 by means 10 of rods 41, which are adjustable as to height within the sleeves 42 and 43, the rods being held in their adjusted position by means of set screws 44. The upper carbon is supported by means of bracket 45 from the disk 15 or plate 23. The lower carbon 4 is movable within and to some extent is guided by the tube 2 and is maintained in normal contact with the upper carbon when no current is flowing through the lamp by means of a 20 counter-weight system, which, with its adjusting clutch construction, forms a material part of my present invention. In the absence of the counter-weight, or when relieved of its control, the carbon itself and its carbon 25 holder drop of their own weight moving the carbon downwardly in the tube 2, the arm 46 passing through the slit 47 to permit such movement. The chain 48 passes over the pulley 50, which may be a sheave wheel when 30 a chain is used. The chain connects the arm 46 and the counter-weight 49, the junction at each end being formed in any suitable manner so that movement of the one results in movement of the other in the reverse direction. By this means, it will be evident that 35 a complete gravity control is obtained free from spring complication. The counterbalancing weight normally lifts the carbon which at once drops when the weight is 40 lifted.

The control of the carbon is effected by 45 means of a solenoid, which, in the particular lamp shown, is placed in series with the arc and whose current varies therefore directly 50 with the current consumed in the lamp. The lamp may, however, be used either in series or in multiple and when in multiple one or more across the main terminals. The solenoid may be replaced by other electro-magnetic apparatus either in series or shunted 55 across the arc. The solenoid is of the double type and is shown at 11. It works upon a U-shaped armature 51, which is consequently drawn into the solenoid or permitted to be withdrawn therefrom according to the amount of current passing through the lamp. The solenoid is preferably attached to though insulated from the lower plate of my lamp and the connections herein described are such as are desirable for this position of the solenoid. It will be evident that the solenoid might instead be otherwise located, as for instance, upon the upper plate 60 and that the form of mechanical connection 65 by means of which its action is brought to

bear upon the clutch might be varied while making use of part of my invention. In the form shown, the U-shaped armature is suspended by means of a rod 52 from a frame or lever 53, preferably of yoke type, which lever is pivoted at 55. Upon one side of the pivot, the lever or frame is provided with a weight 55 for the purpose of overcoming the weight of the U-shaped armature and withdrawing the armature from the magnet after the current has ceased to pass through the solenoid coils. The weight 55 is constructed in the form of a rod which supports at its bottom the second member preferably the cylinder 10, of the dash pot 9, but a flexible connection and heavy dash pot with or without a separate weight might be used. The rod and cylinder as shown are together of sufficient weight to avoid the necessity of additional weighting of these parts. 85

I have illustrated the frame or lever in what I consider the most desirable form, namely as consisting of a strip or rod whose middle portion 56 preferably forms the point of attachment of rod 52, connecting with the armature, which rod is shown passing through an aperture 57 therein, but which might evidently be differently connected. The middle, which may be termed the rear portion of this strip forms the connection between two side branches, which are of the same general character, being, however, reversal of each other and one of them providing attachment for the rod 55. Each of these arms or side members extends substantially at right angles to the rear or middle portion, is outwardly turned at 58, again turns at substantially a right angle at 59 and is turned inwardly at 60 and a portion of it is cut away at 61 within this part 60 for the purpose of permitting movement of a link along the bar 62, thus formed, as best shown in Fig. 2. 95

The link or hanger 63 engages the outer end 64 of one member of a clutch 65, the other member of which is engaged by a link having corresponding connection with the bar formed in the end of the opposite arm. My clutch is formed of two plates 66, which are pivoted preferably at or near their center 115 at 67 so that the plates can move about this pivot when the solenoid is operated. The weight of the rod 55 and its cylinder normally overcoming the weight of the parts upon the opposite side of the pivot of this lever, the 120 ends of the lever in proximity to the clutch normally rest upon the clutch, when there is no current in the lamp and the clutch rests at a point nearer its center upon the top of the guide or tube 2 except as hereinafter described. The result is that the outer ends of the clutch arms 63 are held down and the clutch is supported at a point between these outer points and its center so that the central portion of the clutch is normally lifted 125 130

up to some such position as that shown in Fig. 2. The clutch members themselves consist of two jaws 68 and 69, which are supported from the clutch plates upon opposite sides of the center and at such distance therefrom as to be normally free from contact with the chain or other conductor used to connect between the parts of my system, but these clutch members are tightened upon the chain and brought into action by lifting their outer ends as by action of the solenoid. The points of support of the clutch jaws swing about the center upon which the clutch plates are pivoted with the result that the jaws are made to clutch the flexible conductor when the plates are lifted.

Upon the top of my tube 49, I preferably fasten or secure a plate 70, which is bent right angularly so as to make contact with the outer surface thereof and which is secured by an adjustable fastening 71. The end 72 of this plate reaches far enough into the interior of the tube to engage with the inner ends of the plates of my clutch. As this plate 70 is adjustable as to height, the point of release of the clutch may be adjusted with great nicety. This construction is shown best in Fig. 3, where the clutch and release mechanisms are shown in section.

It will be evident that in my illustration, I have arranged the clutch to be operated by a downward movement of the armature into the solenoid through the system of levers described, but that the solenoid could be so placed as to omit the necessity of some of these levers. While I have shown my clutch as moving upwardly in operation to grasp the chain between the pulley and the weight, it will be evident that the weight might be lifted by pulling down upon the flexible connection, upon the opposite side of the pulley. The current reaches the lamp through binding post 31, traverses the conductor in tube 29, the coils 20 on cores 18 and 19, then the coils of the solenoid 11 from which it passes to the lower carbon and across the arc to the upper carbon and to the binding post 32 by means of the conductor within the tube 30.

In the absence of current through the lamp, the weight of the lower carbon holder and its carbon are overcome by my weight 49, which therefore tends constantly to press the lower carbon up against the upper carbon of the lamp. When the current is passed through the lamp it passes through the solenoidal coils in series in the form shown, balancing its electromagnetic effect and the weights of rod 52 and the armature and of the lower carbon holder and carbon against the weight 49, the rod 54 and the shell 10 of the dash pot 9. These are sufficient at all times to insure the proper withdrawal of the armature 51 from the solenoidal coils when no current is flowing and of course move the armature 51 to a position where the weights

are just compensated by the drawing power of the solenoid when normal current passes.

It will be understood that while I have shown the guide for my weight 49 as consisting of a tube 7, which is preferably air tight below and which makes the weight combine the functions of weight and dash pot piston or disk, a part advantage of my invention may be obtained by using some other form of guide for the weight which omits the dash pot function, or by maintaining the dash pot and using a mere disk to obtain the dash pot effect, attaching a weight thereto or suspending it in such a manner as to cause the weight and disk or piston to move together. In claiming my invention therefore where I associate the functions that I purpose covering the combination of these functions whether the weight be distinct and above or below the dash pot disk or piston or constitute this piston. It will be further evident that the solenoid may be secured in the upper part of my lamp instead of below and that in such case the pivoted frame, which I have illustrated may be omitted and the electro-magnetic means of moving the clutch may be applied to the clutch with or without an associated dash pot.

It will be evident that my use of a plurality of dash pots instead of a single dash pot is advantageous chiefly because the dash pots are placed at different points in my system. One acts directly upon the carbon holder independently of any lost motion between it and the clutch or clutch operating mechanism while the other damps the clutch operating mechanism.

It will be evident that various changes may be made by those skilled in the art which will come within the scope of my invention, and I do not therefore desire to be limited to the exact description herein shown and described.

Having thus described my invention, what I claim as new and desire to secure by Letters Patent, is:—

1. In an inverted arc lamp, a frame, an upper fixed carbon holder, movable lower carbon holder, a counter-weight, a flexible connection between the carbon holder and the counter-weight, a clutch to engage the flexible connection directly moving the counter-weight, and electro-magnetic means for operating the same.

2. In an inverted arc lamp, a frame, an upper fixed carbon holder, a movable lower carbon holder, a counter-weight tending to move it upwardly, a flexible connection between the carbon holder and the counter-weight secured to said counterweight, a clutch adapted to grasp the flexible connection, a yoke supporting said clutch and electro-magnetic means for moving the yoke to lift the counter-weight.

3. In an inverted arc lamp, a frame, a

fixed carbon holder, a movable carbon holder, a counter-weight for the movable carbon holder, a flexible connection between the carbon holder and the counter-weight 5 secured to said counterweight, a clutch surrounding the flexible connection, a frame for the clutch adapted to operate the same to cause it to engage the flexible connection, and electro-magnetic means for moving the 10 frame.

4. In an inverted arc lamp, a frame, an upper fixed carbon holder, a lower movable carbon holder, a counter-weight, a pulley, a flexible connection from said carbon holder 15 over said pulley to said weight maintaining the carbon holder in raised position, a clutch engaging the flexible connection on the weight side of the pulley, and electro-magnetic means for operating said clutch.

20 5. In an inverted arc lamp, a frame, an upper fixed carbon holder, a lower carbon holder, a weight, a flexible connection between the weight and holder, a pulley over which said flexible connection passes, a guide 25 for said weight, a clutch engaging the flexible connection upon the weight side of the pulley, a yoke supporting said clutch and operating it to engage the flexible connection with movement of the yoke, pivots for said 30 yoke, and electro-magnetic means for moving said yoke.

6. In an inverted arc lamp, a frame, an upper fixed carbon holder, a lower carbon holder, a weight adapted to maintain said 35 lower holder in raised position, a flexible connection between the weight and holder and secured to said weight, a pulley over which said flexible connection is passed, a clutch engaging said flexible connection, a frame 40 for operating said clutch, a dash pot and connections restraining movement of said frame, and electro-magnetic means for causing the frame to operate the clutch.

7. In an inverted arc lamp, a frame, an 45 upper fixed carbon holder, a lower carbon holder, a pulley, a flexible connection passing over said pulley, a weight at the opposite end of said flexible connection adapted to overcome the weight of the lower carbon holder 50 and of the carbon, a guide for said weight, a clutch engaging the flexible connection, a frame supporting and operating said clutch, a dash pot and connections opposing movement of said frame, and electro-magnetic 55 means for moving the frame and operating the clutch.

8. In an inverted arc lamp, a frame, an upper fixed carbon holder, a lower carbon holder, a flexible connection attached thereto, 60 a pulley about which said flexible con-

nexion is passed, a weight upon the other end of the flexible connection, a dash pot tube within which said weight is adapted to move as a piston, a clutch engaging said flexible connection to lift the weight, a flexible suspension for said clutch, a frame over which the clutch is suspended, and electro-magnetic means for operating the frame. 65

9. In an inverted arc lamp, a frame, an upper fixed carbon holder, a lower movable carbon holder, a weight and connections attached thereto tending to cause movement of said lower carbon holder, means for moving the weight and a damper directly connected with said weight retarding the said movement. 70

10. In an inverted arc lamp, a frame, an upper carbon holder, a lower carbon holder, a weight tending to maintain the carbon holder in a raised position, and a dash pot 80 cooperating with said weight to retard the movement of the carbon holder.

11. In an inverted arc lamp, a frame, an upper carbon holder, a lower carbon holder, a weight in excess of the weight of the carbon holder and carbon, a flexible connection between the carbon holder and weight, a cylinder surrounding said weight and for which said weight acts as a dash pot piston, and electro-magnetic means for raising the 90 weight. 95

12. In an inverted arc lamp, a frame, an upper fixed carbon holder, a lower carbon holder, a weight and chain for maintaining it in raised position, a dash pot directly controlling the movement of the carbon holder, means for intermittently operating the carbon holder, and a dash pot retarding the operation of the weight. 100

13. In an inverted arc lamp, a frame, an upper fixed carbon holder, a lower carbon holder, a weight and connections exerting an upward pull on said carbon holder, and a cylinder directly damping the movement of said weight. 105

14. In an inverted arc lamp, a frame, a fixed upper carbon holder, a movable lower carbon holder, a weight in excess of the weight of the lower carbon holder and carbon, a pulley, a flexible connection between the lower carbon holder and the weight passing over the pulley, a damper-cylinder surrounding said weight, and electro magnetic means on the weight side of the pulley for lifting said weight. 110
